UNITED STATES PATENT OFFICE.

HARRY M. SCHADEWALD, OF PHILADELPHIA, PENNSYLVANIA.

BEARING FOR LOOM PICKER-STICKS.

SPECIFICATION forming part of Letters Patent No. 588,660, dated August 24, 1897.

Application filed September 17, 1896. Serial No. 606,095. (No model.)

To all whom it may concern:

Be it known that I, HARRY M. SCHADEWALD, a citizen of the United States, residing at Philadelphia, in the county of Philadelphia and State of Pennsylvania, have invented a certain new and useful Improvement in Bearings for Loom Picker-Sticks, of which the following is a specification.

My invention relates to a new and useful improvement in bearings for loom picker-sticks, and has for its object to provide a metal bearing for the lower end of said stick, by which means the wear and breakage which have heretofore taken place will be overcome and the life of the stick greatly increased.

Great annoyance and loss of time, as well as expense, have been heretofore occasioned by the constant wear and breakage of picker-sticks at the point where they are pivoted to the loom-frame, and when a stick is rendered useless by such wear or breakage it is necessary to stop the loom and remove the old stick, replacing it with a new one, and, as is well known by those skilled in the art, this requires considerable time, all of which results in a loss of product of the loom. These disadvantages I have entirely overcome by providing a metal bearing which may be quickly attached to or detached from a picker-stick.

In order that those skilled in the art to which this invention appertains may understand how to make and use the same, its construction and operation will now be described in detail, referring to the accompanying drawings, forming a part of this specification, in which—

Figure 1 is a perspective of a portion of a loom frame and lay, showing a picker-stick attached thereto by my improvement; and Fig. 2, a detailed perspective of the lower end of the picker-stick and the bearing removed therefrom.

In carrying out my invention I provide a semicircular plate A, with which is formed a box B, or, if desired, this box may be formed of a separate piece and secured by rivets or otherwise to the plate. Within the box is a half-bearing C, adapted to fit the pivot-bolt D, which projects from the stud E, the latter being of ordinary construction and arrange-

ment, and from the inner surface of the box project prongs F, so that when the box is to be attached to the picker-stick G it is only necessary to place said prongs in proper position against the inner edge of said stick and embed them therein by sufficient force, after which a screw passed through the hole H, formed in the plate, and into the face of the picker-stick will securely hold the box and plate in position upon said stick. A half-bearing I is formed in the edge of the picker-stick which corresponds with the half-bearing in the box, so that the pivot-bolt D is inclosed upon one side by the bearing I and upon the other by the bearing C. From this it will be seen that when a picker-stick is thus pivoted to the stud E and the loom is in operation the thrust upon the lower end of the picker-stick which is incident to the action of the sweep in causing said stick to throw the shuttle will be received by the bearing in the box, and as this may be made of steel or other suitable metal it is obvious that but little wear will be brought about by this thrust, and, further, that it will be impossible to split the picker-stick at its lower end, as no strain comes upon the grain of the wood passing through the bearing-hole, as is the case in picker-sticks as now used.

The return movement of the picker-stick, occasioned by a suitable spring, causes the bearing in the stick to act upon the pivoting-bolt, but as this movement performs no work it is obvious that but little strain will be exerted upon this bearing; but to prevent the liability of considerable wear taking place upon the bearing I the hole J is made to fit the bolt D snugly, thereby causing the plate to receive a portion of the strain incident to the reverse movement of the picker-stick.

As now constructed the life of a picker-stick is very short, as it is constantly liable to split at the point where the pivoting-hole is formed, as such a stick is subjected to an enormous strain and jar by the rapid movements and sudden stops which are necessarily transmitted thereto by the actions of the loom.

One of the advantages of my improvement is that it may be readily attached to a picker-stick with little or no alteration of the latter, and when the stick has become worn or

useless from any cause it may be removed and attached to another stick.

Having thus fully described my invention, what I claim as new and useful is—

- 5 In combination with a picker-stick having a semicircular bearing formed in one edge near the end, a plate having a circular opening therethrough, a right-angular flange formed on the plate, said flange running
- 10 around one edge of the opening thereby forming a semicircular depression in the flange in alignment with the opening, prongs formed on the flange on either side of the opening,

said plate being secured against the side of the stick, with the flange fitting against the 15 edge thereof, the semicircular depression forming a complete bearing with the semicircular bearing in the stick, substantially as described.

In testimony whereof I have hereunto affixed my signature in the presence of two subscribing witnesses.

HARRY M. SCHADEWALD.
